UNITED STATES PATENT OFFICE

HERBERT S. WALKER, OF MAMARONECK, NEW YORK, ASSIGNOR TO WALKER & FORBES, INC., OF MAMARONECK, NEW YORK, A CORPORATION OF NEW YORK

ROD OR SHAFT PACKING

Application filed August 15, 1927. Serial No. 213,047.

The invention aims to provide a new and improved packing for rods and shafts, embodying folded soft metal strips, yet of such construction that it is sufficiently flexible to be wrapped around a rod or shaft of one diameter or another, the packing being of such nature that it may be effectively compressed and forced into tight contact with the rod or shaft by tightening of the usual gland of the stuffing box or the like with which the packing is used.

With the foregoing in view, the invention resides in the novel subject matter hereinafter described and claimed, the description being 15 supplemented by the accompanying drawings.

Fig. 1 is a perspective view of a packing constructed in accordance with my invention.

Fig. 2 is a sectional perspective view showing the packing of Fig. 1 secured in a channel-shaped shell of fabric, asbestos or the like.

Figs. 3 and 4 are sectional views on the correspondingly numbered lines of Fig. 1.

Fig. 5 is a perspective view showing a different form of packing in which four folded metal strips are used instead of two as in the first form of construction.

Fig. 6 is an end elevation partly broken away showing the relation of the numerous reaches of the metal strips in the form of construction shown in Fig. 5.

Fig. 7 is a sectional view on line 7—7 of Fig. 6.

Figs. 8 and 9 are views similar to Fig. 6 but showing still further forms of construction.

In the construction shown in Figs. 1 to 4, two pliable metal strips 10 and 11, formed of tin, lead or other soft metal, are folded back and forth across each other to provide a multiplicity of contacting, interconnected reaches 10^a and 11^a, the bends 10^b and 11^b at the ends of such reaches, extending around and contacting with longitudinal edges of the strips. 45 By this construction, any desired number of the interconnected reaches 10^a—11^a may be provided, to form an elongated packing member of any desired length and it will be obvious that due to the pliability of the metal, 50 this packing member may readily flex to per-

mit wrapping thereof around shafts or rods of different diameters.

Preferably, all reaches of the packing are secured together with a filler or binder of rubber, gutta-percha or the like and this substance may be used for holding said packing in a channel-shaped shell 12 such as that shown in Fig. 2. This shell may be formed of fabric, asbestos or any other desired material and its open side exposes the metallic packing for contact with the rod or shaft. When the packing is installed in a stuffing box or the like and the gland thereof is tightened, said packing is laterally compressed so that radial expansion thereof takes place, causing tight contact with the shaft or rod to prevent leakage.

The completed packing may of course be lubricated with any of the known lubricants, such as tallow, hydro-carbon oils of high heat resistance in conjunction with graphite, mica or other analogous substances.

In the form of construction shown in Fig. 5, I make use of four pliable metal strips 13—13' and 14—14', in forming the numerous reaches of the packing. The two strips 13—13' are folded back and forth across the strips 14—14' and similarly these strips 14—14' are folded back and forth across the strips 13—13'. This provides a plurality of reaches 13^a—13^b formed by the strips 13—13', and a plurality of reaches 14^a—14^b formed by the strips 14—14'. The strips 13—13' are folded in opposite directions to provide the reaches 13^a—13^b as will be clear from Fig. 6, 85 and these reaches lie edge to edge. Similarly, the strips 14—14' are folded in opposite directions to form the reaches 14^a—14^b and these reaches likewise lie edge to edge. The bends 13^c and 13^d of the strips 13—13', extend around and contact with the outer edges 90 of the reaches 14^a—14^b. Similarly, the bends 14^c—14^d of the strips 14—14', extend around and contact with the outer edges of the reach 13^a—13^b.

Fig. 8 discloses a construction similar to that illustrated in Figs. 5 and 6. Whereas in Figs. 5 and 6 however, the reaches 13^a—13^b are disposed edge to edge in a common plane throughout their areas and the same is true 100

of the reaches 14^a—14^b, the four metal strips 15—15' and 16—16' of Fig. 8 are so bent that their reaches 15^a—15^b and 16^a—16^b, are virtually interwoven in much the same fashion as the splints of a market-basket.

5 In the form of construction illustrated in Fig. 9, three metal strips 17—17'—18, are used. The strips 17—17' are folded back and forth across the single strip 18 providing reaches 17^a—17^b, and similarly the strip 18 10 is folded back and forth across said strips 17—17', providing reaches 18^a. Longitudinal edges of the strips in this form of construction as well as in that shown in Fig. 8 15 are seated in the bends or folds of the metal strips. Moreover, it will be understood that these constructions and that shown in Fig. 7 may embody a suitable elastic filler or binder and may if desired be associated with a flexible shell such as 12 of Fig. 2.

20 Any form of the invention may be easily and inexpensively manufactured, may be applied with ease on account of its unusual flexibility, and when compressed by the usual gland or the like of a stuffing box, will provide an effective fluid-tight seal.

25 As above stated, variations may be made within the scope of the invention as claimed and obviously I am not restricted to size or materials.

30 I claim:—

35 1. In a packing, flexible strips folded back and forth across each other to provide a multiplicity of contacting interconnected reaches which jointly form an elongated body, the 40 folds of any of said strips being disposed around and in contact with longitudinal edge portions of another of said strips.

45 2. In a packing, a plurality of flexible strips, another strip or strips across which said plurality of strips are folded back and forth, said other strip or strips being also folded back and forth across said plurality of strips, providing a multiplicity of contacting interconnected reaches which jointly form an elongated body.

50 3. A structure as specified in claim 2; adjacent reaches of the strips of said plurality being folded in opposite directions.

55 4. In a packing, flexible strips folded back and forth across each other to provide a multiplicity of contacting interconnected reaches which jointly form an elongated body, the fold lines of any of said strips being disposed longitudinally of longitudinal edge portions of another of said strips.

In testimony whereof I have hereunto affixed my signature.

HERBERT S. WALKER.
